UNITED STATES PATENT OFFICE.

ANDREW R. WILBUR, OF BALTIMORE, MARYLAND.

MAKING SPIRAL SPRINGS.

SPECIFICATION forming part of Letters Patent No. 234,830, dated November 23, 1880.

Application filed October 8, 1880. (No model.)

To all whom it may concern:

Be it known that I, ANDREW R. WILBUR, of Baltimore city, State of Maryland, have invented a new and Improved Tool for Making 5 Wire Spirals; and I do hereby declare that the following is a full, clear, and exact description of the same.

My invention relates to an improved hand-tool to be used principally by jewelers, that 10 will enable them to rapidly make small wire spirals for shirt-studs; and the improvement consists, primarily, in a mandrel secured to an ordinary tool-handle, a carrier fitted upon the lower end of the mandrel to revolve around it, 15 and a presser-bar pivoted upon the carrier, the parts being so arranged that the wire may be secured at one of its ends to the end of the mandrel and the presser-bar held against the wire and revolved around the mandrel and 20 moved up and down upon the same and coil the wire closely around it.

My invention also consists in certain details of construction, hereinafter more fully described, and particularly pointed out in the 25 claims.

In the accompanying drawings, Figure 1 is a side elevation of the improved tool; Fig. 2, a perspective view of the wire-holder; Fig. 3, a similar view of the end of the mandrel upon 30 which the said wire-holder fits; Fig. 4, an enlarged sectional detail of the eye-plate that holds the end of the wire while it is being coiled. Fig. 5 is a perspective view, in detail, of a spiral formed by the improved tool; 35 and Fig. 6, a sectional plan, in detail, in line $x x$ of Fig. 1.

An ordinary tool-handle, A, such as is used upon awls and files, has secured to its end a rod or mandrel, B, of a size to correspond with 40 that of the spiral, H, to be formed. The end of the mandrel nearest the handle is formed with a screw-thread of a pitch to conform to that of the spiral.

The carrier is formed of a nut, C, post D, 45 guide-lever I, and presser-bar E. The nut is screw-threaded to fit the mandrel, so that as it revolves the carrier will be revolved and moved upon the mandrel from end to end.

The presser-bar is pivoted upon the end of the 50 post above the guide-lever I, which latter is

journaled upon the mandrel to hold the carrier firmly in place upon the mandrel, and the presser-bar is pivoted above said guide-lever in such manner that the outer end of lever E may be pressed upon with the ends of 55 the fingers to firmly hold the other end against the mandrel and press upon the wire. A collar, F, upon the mandrel will determine the length of the movement of the carrier.

A thimble-shaped holder, G, is made to snugly fit over the end of the mandrel, and is formed with an eye-plate, g, arranged diametrically across its end, that fits in a slot, b, in the end of the mandrel. The plate g has a hole, g', that passes through it, and is of a size to receive the end of the wire. When the end of the wire is placed in the hole g' a suitable distance it is bent down at right angles, so that it will pass beneath the plate and through the slot b to the outside of the mandrel. By this 60 means the end of the wire is securely held when the presser-foot is forced against it to 65 bend the wire.

In using the instrument the handle is held and revolved by one hand, while the mandrel 70 is held by the ends of the fingers of the other hand, so that the presser-bar will rest upon the fingers and be prevented from turning when the handle and mandrel are turned.

Instead of securing the end of the wire to 75 the mandrel in the manner described, it may simply be passed through a diametrical hole through the end of the mandrel and the crook be made upon the end of the coil by a pair of pinchers after the coil has been formed. The 80 crook or twist in the other end of the coil may be made by bending the wire around the presser-bar and then cut off at the required length.

The tool may be made to work with good 85 effect without the screw-thread upon the mandrel; but the convolutions of the wire will not be formed so regularly and quickly as when the screw-feed is used in connection with the carrier.

The above-described tool may be used for 90 coiling wire to form springs, or for any similar purpose.

What I claim as new is—

1. In a tool for bending wire into coils or 95

spirals, the combination of the handle, the mandrel provided with means for holding the end of the wire, and a carrier journaled upon the mandrel to revolve and move along its 5 length, these parts being combined and arranged to operate substantially as described.

2. The handle having screw-threaded mandrel, in combination with the nut encompassing the screw-threaded portion of the mandrel, the post attached to said nut, the guide-lever pivoted around the mandrel and connected with the end of the post, and a presser-bar pivoted to the top of the guide-lever and

adapted to co-operate with the guide-lever, as described.

3. The combination, with the mandrel B, having a diametrical slot, *b*, in its end, of the thimble G, arranged to fit over the end of the mandrel and having a diametrical plate, *g*, arranged to fit in the slot *b*, and having a central hole, *g'*, substantially as and for the purpose described.

ANDREW RYLAND WILBUR.
